(57) **CLAIM**

The ornamental design for an adjustable mounting bracket, as shown and described.

DESCRIPTION

FIG. 1 is a perspective view of a first embodiment of the adjustable mounting bracket.

FIG. 2 is a front view of the first embodiment of the adjustable mounting bracket.

FIG. 3 is a back view of the first embodiment of the adjustable mounting bracket.

FIG. 4 is a left side view of the first embodiment of the adjustable mounting bracket, the right side view of the adjustable mounting bracket being a mirror image thereof. FIG. 5 is a top view of the first embodiment of the adjustable mounting bracket.

FIG. 6 is a bottom view of the first embodiment of the adjustable mounting bracket.

FIG. 7 is a perspective view of the second embodiment of the adjustable mounting bracket.

FIG. 8 is a front view of the second embodiment of the adjustable mounting bracket.

FIG. 9 is a back view of the second embodiment of the adjustable mounting bracket.

FIG. 10 is a left side view of the second embodiment of the adjustable mounting bracket, the right side view of the adjustable mounting bracket being a mirror image thereof. FIG. 11 is a top view of the second embodiment of the adjustable mounting bracket; and,

FIG. 12 is a bottom view of the second embodiment of the adjustable mounting bracket.

The evenly-spaced broken lines in FIGS. 1-10 illustrate portion of the adjustable mounting bracket that form no part of the claimed design. The dash-dot broken lines in FIGS. 1-3 and 7-9 illustrate the boundary of the claimed design which forms no part thereof.
